(57) **CLAIM**

What is claimed is the ornamental design for a triple hook, as shown and described.

DESCRIPTION

FIG. 1 is a perspective view of a triple hook showing a new design;

FIG. 2 is a top view of the triple hook of FIG. 1;

FIG. 3 is a front view of the triple hook of FIG. 1;

FIG. 4 is a side view of the triple hook of FIG. 1;

FIG. 5 is a bottom view of the triple hook of FIG. 1; and,
FIG. 6 is a rear view of the triple hook of FIG. 1.

The components of the display shown in broken lines illustrate portions of the triple hook form no part of the claimed design.
